CLAIM

The ornamental design for a patient-supporting panel of an operating table, substantially as shown and described.

DESCRIPTION

FIG. 1 shows a perspective view of a patient-supporting panel of an operating table showing our new design,

FIG. 2 shows a head end view thereof;

FIG. 3 shows a foot end view thereof;

FIG. 4 shows a right side view thereof;

FIG. 5 shows a left side view thereof;

FIG. 6 shows a top view thereof; and,

FIG. 7 shows a bottom view thereof.

The broken lines are included for the purpose of illustrating portions of the patient-supporting panel of an operating table that form no part of the claimed design.
